(57) **CLAIM**

The ornamental design for a mount for a cycle as shown and
described.

DESCRIPTION

FIG. 1 is a top, front, and right side perspective view of a
mount for a cycle in accordance with the present invention;

FIG. 2 is a right side elevation view thereof;

FIG. 3 is an left side side view thereof;

FIG. 4 is a top plan view thereof;

FIG. 5 is a bottom plan view thereof;

FIG. 6 is a front elevation view thereof; and,

FIG. 7 is a rear elevation view thereof.

In the drawings, elements shown in broken lines form no
part of the claimed design.

1 Claim, 7 Drawing Sheets
